US00D856275S

(12) **United States Design Patent** (10) **Patent No.:** **US D856,275 S**
Laurino et al. (45) **Date of Patent:** **** Aug. 13, 2019**

(54) **DETACHABLE POWER SUPPLY FOR DATA LOGGER**(71) Applicant: **Fluke Corporation**, Everett, WA (US)(72) Inventors: **Ferdinand Y. Laurino**, Seattle, WA (US); **Matthew Bannister**, Lake Stevens, WA (US)(73) Assignee: **Fluke Corporation**, Everett, WA (US)(***) Term: **15 Years**(21) Appl. No.: **29/647,305**(22) Filed: **May 11, 2018****Related U.S. Application Data**

(62) Division of application No. 29/593,850, filed on Feb. 13, 2017, now Pat. No. Des. 818,947, which is a division of application No. 29/523,201, filed on Apr. 7, 2015, now Pat. No. Des. 782,972, which is a division of application No. 29/441,514, filed on Jan. 7, 2013, now Pat. No. Des. 726,647.

Primary Examiner — Deanna L Pratt(74) *Attorney, Agent, or Firm* — Seed Intellectual Property Law Group LLP(57) **CLAIM**

The ornamental design for a detachable power supply for data logger, as shown and described.

DESCRIPTION

FIG. 1 is a top front right perspective view of a detachable power supply for a data logger showing our new design.

FIG. 2 is a bottom front left perspective view thereof.

FIG. 3 is a bottom rear perspective view thereof.

FIG. 4 is a rear elevation view thereof.

FIG. 5 is a front elevation view thereof.

FIG. 6 is a top plan view thereof.

FIG. 7 is a bottom plan view thereof.

FIG. 8 is a right side elevation view thereof; and,

FIG. 9 is a left side elevation view thereof.

1 Claim, 6 Drawing Sheets(56)
